CLAIM

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is an enlarged view of the claimed design shown in FIG. 1 with environment removed for clarity purposes; and, FIG. 5 is an enlarged view of the claimed design shown in FIG. 2 with environment removed for clarity purposes.

The uneven-length broken line immediately adjacent to and surrounding the shaded area defines the peripheral bounds of the claimed design and forms no part thereof. The contrast between the dark stippling visible in FIGS. 1-2 and the hatching shown in FIG. 3 (and their corresponding enlargements) represents a contrast in appearance only. The even-length broken lines within the shaded area and the unshaded regions there between form no part of the claimed design. The uneven-length broken lines depicting the remainder of the shoe show features that form no part of the claimed design.
